UNITED STATES PATENT OFFICE.

JOHN C. HUBBARD, OF WORCESTER, MASSACHUSETTS.

ELECTROSTATIC VOLTMETER.

1,042,440

Specification of Letters Patent. Patented Oct. 29, 1912.

Application filed October 13, 1911. Serial No. 654,444.

To all whom it may concern:

Be it known that I, JOHN C. HUBBARD, a citizen of the United States, residing at Worcester, in the county of Worcester and State of Massachusetts, have invented a new and useful Electrostatic Voltmeter, of which the following is a specification.

The principal objects of the invention are to provide a voltmeter or electrometer of very great sensitiveness; to provide means whereby an ordinary form of electroscope can, by very simple and inexpensive additions, be converted into a sensitive electrostatic voltmeter or electrometer; to provide an instrument of the indicated character having a constant sensibility for a given strength of field whereby measures upon large potentials can be made with the same absolute degree of accuracy as upon small potentials; to provide an instrument of this character useful in all measurements commonly made either with the gold-leaf electrometer, quadrant electrometer, or electrostatic voltmeter, and which can be used for alternating current voltages as well as for direct.

Further objects and advantages will appear hereinafter.

Reference is to be had to the accompanying drawings, in which—

Figure 1 is a front elevation of a gold leaf electrometer constructed in accordance with this invention; Fig. 2 is a plan of the same; and Fig. 3 is a diagrammatic view showing the electrical connections.

The invention is shown in a simple form in which a stand 10 is provided having leveling screws 11 for supporting the instrument. On this stand is a shaft 12 to which is fixed a casing 13 of conducting material. This casing is provided with an insulating plug 14 for supporting a mercury terminal 15 with which is connected a gold leaf indicator 16 depending in the casing. At the bottom the casing is provided with an adjusting screw 17 which carries an insulating support 18 on which are mounted two conducting terminals 19 insulated from each other by the support 18 and making an angle with each other. These are so located that under normal conditions the gold leaf 16 depends between the terminals 19 without touching them. A pair of springs 20 engage the terminals 19 and are connected through insulating plugs 21 to binding screws 22. At the sides of the casing oppo-

site the indicator are windows 23 through which the position of the indicator may be observed as for example through a microscope 24 supported by the shaft 12. The shaft 12 is mounted to turn in bearings on the support 10 and is provided with a hub 25 which is engaged by a split bushing 26 on an adjusting frame 27. A screw 28 is provided for clamping the split bushing to the hub of the shaft so that any motion of the frame will be transmitted to the shaft. The frame is provided with an adjusting screw 280 and a spring-pressed plunger 29 both engaging a lug 30 cast on the support 10. The casing 13 is also provided with a disk 33 concentric with the shaft and provided with a scale 31 preferably with a vernier 32 by which the angularity can be read.

It will be obvious that by loosening the screw 28 the casing can be turned to any desired point and then by tightening the screw the frame 27 can be adjusted to any desired degree of fineness thus adjusting the position of the casing in like degree.

The principle of the instrument depends on the fact that when the indicator is charged to a given potential the instrument may be tilted or turned so that the force of gravity, or some other force, constant in magnitude and direction, acting on the indicator will balance the electric force acting on the same in such a way that the indicator will occupy the same position with respect to the other parts of the instrument as it did in the normal position of the instrument before the indicator was charged. The potential or voltage which has been applied to the indicator is then proportional to the sine of the angle ϕ of tilt.

The device is connected up as usual. The diagram (Fig. 3) illustrates the connections. The binding screws 22 are connected with the opposite poles of a battery B or the like giving the field plates 19 a constant potential difference. The middle of the battery, screw 17 and casing 13 are earthed (E). The terminal 15 is connected with a switch S which can be connected to the earth, to a known potential, as a standard cell V_s , for calibration, or to the unknown potential (V_x).

In order to use the instrument in measuring potentials it is first necessary to calibrate it. The case and indicator are put "to earth" while the field plates 19 are put at a constant difference of potential as de-

scribed. The microscope or reading device of the indicator is so adjusted that the indicator stands at a definitely measured place in the field; for instance, when the microscope is used, the image of the indicator is seen to coincide with a cross hair or mark at the focus of the eye-piece of the said microscope. The earth connection with the indicator is now broken, and the indicator is connected with one pole of a standard cell of potential V_s , the other pole being to earth. Then

$$k = V_s / \sin. \varphi.$$

15 Using this value of k it is then possible to measure any unknown potential by connecting it in place of the standard cell. The unknown potential may also be measured by direct comparison. Let V_s be the known potential, V_x the unknown, φ_s the angular reading for the known potential, and φ_x the angular reading for the unknown potential, then

$$V_x = (V_s \sin. \varphi_x) / \sin. \varphi_s$$

25 The theory may be stated in a more general way as follows: Let the indicator be suspended or supported in an electric field produced between the plates 19 charged to a definite difference of potential. Suppose now that the indicator be uncharged or put to some definite potential which, for convenience, we shall call zero, and let the position of the indicator with reference to the plates 19, or with reference to any bodies which produce the field be measured. Call this the zero position of the indicator. Now let the indicator be charged to the potential which is to be measured. The indicator will be deflected or turned by the electric field acting upon the charge on the indicator. The framework or case which carries the system of field bodies and the support of the indicator is now turned or rotated in such a direction that the indicator is drawn by some force, constant in direction and magnitude, such as the force of gravity, back into its original position with reference to the field and the system which produces it. The indicator is now in equilibrium under the action of two forces, (a) the deflecting force of the electric field, and (b) the restoring force, (gravity). Let the angle through which the instrument has been turned be φ .
55 Then we have

$$V = k \sin. \varphi,$$

where V is the potential to be measured, *i. e.*, that applied to the indicator, k is a constant of the instrument which depends upon the strength of the field and upon the density and structure of the indicator, and φ is the angle through which the instrument has been turned in order to restore the indicator to its initial position. For, consider

any portion of the indicator. The force G , which has been called the restoring force is constant in magnitude and direction and exerts the moment

$$aG = Gr \sin. \varphi,$$

when a is the perpendicular distance from the line of action of the force G to the point of support of the indicator, and r is the distance from the point considered to the axis of support.

Let the force F be the component of the electric force acting at the same point perpendicular to the radius to the point from the axis of support. This force is, by electrical theory, proportional to the potential applied to the indicator, that is $F = KV$, since by the manipulation of the instrument above described, the indicator is in a field of constant strength and fixed direction with respect to the indicator. The moment of this force is KVr . These two moments are equal and opposite, or,

$$KVr - Gr \sin. \varphi = 0.$$

90 Since this is true for any portion of the indicator it is true for all portions and we have, therefore,

$$V = (G/K) \sin. \varphi = K \sin. \varphi,$$

95 as stated.

Although I have illustrated and described the invention as applied to a gold leaf electroscope, it is to be understood that this is done for illustrative purposes and I do not wish to limit myself thereto, but

What I do claim is:—

1. In an electrostatic-voltmeter, the combination of an indicator adapted to be charged and to be moved, a pair of terminals adapted to be connected with a constant source of electricity to keep them at a constant potential difference for influencing the indicator to move it, a casing for supporting the terminals and indicator, and means whereby said casing can be moved to bring the indicator when charged back to the position it assumed when not charged.

2. In a device of the character described, the combination with a movable casing, of a support thereon, an indicator on the support adapted to be charged and to be moved thereby, a pair of terminals carried by the casing on opposite sides of the indicator for connection with the opposite poles of a constant source of electricity to keep them at a constant potential difference, and means whereby the casing can be moved for the purpose of restoring the indicator to its uncharged position by the aid of an independent force while the indicator and terminals are charged.

3. In a device of the character described, the combination of a casing having a support thereon, a freely movable indicator car-

ried by said support, a pair of terminals insulated from each other and mounted on said casing in position to influence the indicator when charged to cause the indicator 5 to move, and means whereby said casing can be rotated on an axis for the purpose of bringing the indicator back to its uncharged position by the aid of gravity when charged.

4. In a device of the character described, 10 the combination with a support, of a shaft supported thereon and capable of being turned by hand, a casing fixed to the shaft, an indicator in the casing, means for electrically influencing the indicator, an adjustable frame connected with said support and mounted at one end of said shaft, and means 15 for fixing said frame to the shaft, whereby the shaft can be turned by the adjustment of the frame.

20 5. In a device of the character described, the combination with a support, of a shaft

rotatably supported thereon, a casing fixed to the shaft, an indicator in the casing, means for electrically influencing the indicator, an adjustable frame connected with 25 said support and mounted at one end of said shaft, means for fixing said frame to the shaft, whereby the adjustment of the frame will rotate the shaft, a disk fixed on said shaft concentric therewith, and having a 30 scale thereon for showing the amount of adjustment, and a microscope carried by said shaft beyond said frame by which the position of the indicator can be read.

In testimony whereof I have hereunto set 35 my hand, in the presence of two subscribing witnesses.

JOHN C. HUBBARD.
